DIFFERENTIAL ADJUSTMENT FOR CONDITION RESPONSIVE DEVICES

Clarence W. Kuhn, Wauwatosa, Wis., assignor to
Cutler-Hammer, Inc., Milwaukee, Wis., a corporation of Delaware

Application January 2, 1947, Serial No. 719,640

10 Claims. (Cl. 74—522)

1

This invention relates to condition responsive devices and more particularly to differential adjustment thereof.

In practice differential adjustment has been quite a problem, particularly in connection with sensitive devices, as for example the so-called "microswitch," which as is well known is one usually of the snap type, biased to a given position, being operable to another position by a relatively small force, and being restrainable against its bias by a force less than that required to move it against its bias.

An object of the invention is to provide a differential adjustment for condition responsive devices, including those of the character just mentioned, which may be readily and inexpensively provided for and which will afford adjustment of differential without disturbing the range adjustment or other essential adjustments.

Another object is to provide such a differential adjustment which will enable the differential to be reduced to a very small value and which may be varied in a simple and convenient manner.

Another object is to provide for differential adjustment through the medium of means affording positive drive of the actuating element of the controlled switch or other device by the condition responsive means, as distinguished from drive through a resilient part.

Another object is to provide for differential adjustment through the medium of rugged and durable means.

Other objects and advantages of the invention will hereinafter appear.

One embodiment of the invention is illustrated in the accompanying drawing, it being understood that the embodiment illustrated is susceptible of various modifications without departing from the scope of the appended claims.

In the drawing

Fig. 1 is an elevational view of a condition responsive switch embodying the invention;

Fig. 2 is a top plan view of Fig. 1;

Fig. 3 is a more or less schematic view of means embodied in the device of Figs. 1 and 2;

Figs. 4, 5 and 6 are perspective views of certain elements shown in Fig. 1; and

Fig. 7 is a more or less schematic view depicting the method of assembling the parts shown in Figs. 5 and 6.

Referring to Figs. 1 and 2, they show a device comprising an enclosed switch 1 to be assumed to be of the aforementioned "microswitch" type, said switch being controllable by condition responsive element 2 which will be assumed to be

2

a pressure responsive element, although it might be of any of a number of other types. Switch 1 is shown as attached to an insulating supporting plate 3 in turn attached to an inverted U-shaped frame 4 carried by a right angle plate 5 to which the pressure responsive element 2 is suitably attached. This particular assembly while advantageous is not essential and hence will not be described in detail. The inverted U-shaped frame 4 has mounted therein a loading spring 6 for the pressure responsive element 2, which element may be assumed to be of the diaphragm type and said loading spring has an adjusting screw 7 accessible at the top of frame 4. As will be understood, the adjustable loading spring provides for range adjustment but not for differential adjustment.

Switch 1 has a reciprocable actuating element 10 projecting beyond the enclosure of said switch and directly engaged by a lever 11 which may be formed of rigid material and which has no operative connection with the pressure responsive element except through a lever 12, said levers having a free lost motion connection therebetween. Lever 12 is operatively connected to the unit comprising the pressure responsive element 2 and loading spring 6, and said lever has for engagement with lever 11 on opposite sides of the latter a button 13 and an adjustable screw 14, the head of which screw overhangs the end of lever 11. Thus is provided a free lost motion connection between lever 11 and lever 12; the degree of lost motion is variable by adjustment of screw 14. The lever 11 has means biasing it in a direction tending to press inwardly the switch actuating element 10, the force of such bias of lever 11 being variable by an adjusting screw 15.

As more clearly shown in Fig. 3, lever 12 is a right angle lever and is mounted on a pivot pin 20 adjacent the junction of its perpendicularly disposed arms. The arm 12^a projects between the pressure responsive element 2, here shown schematically as a diaphragm, and the loading spring 6. Lever 12 preferably is of the form shown in Fig. 4, the arm 12^a thereof being of channel form with bearings 12^b in its side flanges for the pivot pin 20, which pin may be and preferably is terminally supported by the inverted U-shaped frame 4 of Figs. 1 and 2. Lever 11 preferably is of the form shown in Fig. 5, having a short perpendicular arm 11^a reflexed to provide a portion 11^b to hook on to the pivot pin 20 between the side flanges of arm 12^a of lever 12. Levers 11 and 12 thus have a common pivotal

axis and lever 11 is biased in a counterclockwise direction by a leaf spring 21 carrying the aforementioned adjusting screw 15 to bear upon a fixed abutment which as will be apparent from Figs. 1 and 2 is afforded by the right angle plate 5. Preferably the spring 21 is of the form shown in Fig. 6, having a transverse slot 21^a to accommodate a cross section of lever 11, an opening 21^b to receive a lug 11^c on lever 11, an opening 21^c to afford clearance for the operating connection between the diaphragm 2 and lever 12^a and a threaded opening 21^d to receive adjusting screw 15. Referring to Fig. 7 the slotted end of spring 21 may be slipped onto the lever 11 as shown in dotted lines and then along said lever to seat the extremity of the spring on the upper flat surface of arm 11^a and to afford the spring an opposed bearing against the free end of the hook 11^b with lug 11^c extending into the opening 21^b of the spring as shown in full lines, thus to securely interlock said spring and lever.

With the construction shown and described adjustment of the spring bias of lever 11 by adjustment of screw 15 enables the switch actuating element 10 to be so conditioned as to permit the switch normally to occupy an open or closed position to which it is inherently biased and yet to be movable to closed or open position, as the case may be, by a very slight movement of lever 11 by a force to be supplied by lever 12. As will be observed such adjustment of the bias of lever 11 is wholly independent of the range adjustment of the device and in fact wholly independent of the pressure responsive means including the loading spring 6. Such adjustment of the bias of lever 11 provides for the reduction in supplemental force required to cause movement of actuating element 10 to actuate the switch. A preferred method of obtaining the desired adjustment is by turning the screw 15 to increase the bias of lever 11 to a degree sufficient to actuate the switch against its inherent bias and then to back off the screw to reduce the bias to the desired degree. The desired degree of reduction of bias of lever 11 is that which renders the bias incapable of preponderating the inherent bias of the switch but rendering it sufficient to restrain the switch in the position to which it is moved against its inherent bias.

It has been found in practice that the desired degree of reduction of the bias of lever 11 may be obtained by backing off screw 15 to such a position that the switch returns to its normal condition and then finally setting it at a point midway between the aforementioned two points of adjustment of the screw which provided for actuation and return of the switch. However, it will be apparent to those skilled in the art that the final position for screw 15 may be on either side of the mid-point.

Then to obtain the desired differential adjustment it is merely necessary to adjust the degree of free lost motion between the levers 11 and 12. The pressure at which the lever 12 engages and supplements the force exerted by lever 11 counterclockwise is determined by the adjustment of loading spring 6 and the lower pressure at which lever 12 engages lever 11 to move it clockwise is determined by the adjustment of screw 14. As aforeslated, when the lever 12 engages and operates lever 11 counterclockwise it effects operation of switch 1 to its open or closed position, as the case may be, in which position the switch is retained by the bias of lever 11, when as the result of falling pressure the lever

12 begins to move clockwise. However, when lever 12 moves clockwise sufficiently to engage the head of screw 14 with lever 11 it positively moves lever 11 in a direction to permit switch 1 to resume its normal open or closed position under its own bias.

What I claim as new and desire to secure by Letters Patent is:

1. In condition responsive means to effect reverse operations of a controlled device biased to a given position, the combination with an element movable in opposite directions, and biasing means for said element adjusted for biasing it unidirectionally to subject the controlled device to a non-operating force sufficient to neutralize its bias, of means responsive to varying conditions and including an element movable in reverse directions selectively as a function of reversals of such varying conditions, and means providing a free lost motion connection between said elements for positive operation by said second mentioned element of the first mentioned element in reverse directions selectively after take-up of the lost motion, the last mentioned means including means to adjust the range of such lost motion, thereby to provide for adjustment of differential independently of adjustments of said means responsive to varying conditions.
2. For control of a device biased from a given position to another given position, the combination with a lever and adjustable biasing means therefor biasing it to subject the controlled device to a non-operating force such as to oppose and neutralize the bias of the latter when in the first mentioned given position, of means responsive to varying conditions and including a lever oscillating as a function of reversals of such varying conditions, and means providing a lost motion connection between said levers which connection subject to take-up of lost motion subjects the first mentioned lever to positive actuation by the second mentioned lever in reverse directions according to the direction of movement of the latter, the last mentioned means comprising means to adjust the range of such lost motion, thereby to provide for adjustment of differential independently of the adjustments of said means responsive to varying conditions.
3. Control means for a device biased from a given position to another given position, comprising two levers, biasing means for one of said levers adjusted for biasing it to subject the controlled device to a non-operating force such as to oppose and neutralize the bias of the latter, and means providing a lost motion connection between said levers whereby subject to take-up of lost motion said biased lever is subject to positive actuation in reverse directions by the other of said levers according to the direction of movement of the latter, said means including means to adjust the range of such lost motion.
4. Control means for a device biased from a given position to another given position, comprising two levers having a common fixed pivotal axis, biasing means for one of said levers adjusted for biasing it to subject the controlled device to a non-operating force such as to oppose and neutralize the bias of the latter, and means providing a lost motion connection between said levers whereby subject to take-up of lost motion said biased lever is subject to positive actuation in reverse directions by the other of said levers according to the direction of movement of the lat-

ter, said means including means to adjust the range of such lost motion.

5. Control means for a device biased from a given position to another given position, comprising two levers having a common pivotal axis and being in a coplanar relation, one of said levers being an actuator for the other and said levers having relatively adjustable parts to provide a lost motion connection between said levers adjustable in respect of range of lost motion, condition responsive means to oscillate said actuator lever and adjustable biasing means for said other lever subjecting the same to a bias opposed to the bias of said device and adjusted to be non-preponderating but sufficient to neutralize the bias of the controlled device, thereby to render said biased lever effective to restrain the controlled device during reverse take-up of lost motion between said levers after the controlled device has been moved out of the position to which it is biased.

6. Control means for a device biased from a given position to another given position, comprising two levers having a common pivotal axis and being in a coplanar relation, one of said levers being an actuator for the other and said levers having relatively adjustable parts to provide a lost motion connection between said levers adjustable in respect of range of lost motion, condition responsive means to oscillate said actuator lever and biasing means for said other lever subjecting the same to a bias opposed to the bias of said device and adjustable to be non-preponderating but sufficient to neutralize the bias of the controlled device, thereby to render said biased lever effective to restrain the controlled device during reverse take-up of lost motion between said levers after the controlled device has been moved out of the position to which it is biased, said biased lever having a hooked portion for its pivotal bearing and its said biasing means comprising a leaf spring apertured to be slipped onto said lever for confinement of its extremity behind said hooked portion and for obtaining an opposed bearing against the free extremity of said hooked portion.

7. In combination, a device biased to a given position and comprising means which renders movement from such given position to a second position and vice versa dependent upon relative variations between its biasing force and an opposing force and which insures full movement of said device when leaving either position, a cooperating element movable in opposite directions, and having means constantly biasing it unidirectionally to subject said device to a non-operating force sufficient to neutralize the bias of said device thus to restrain said device against return movement, means responsive to varying conditions including an element movable in reverse directions selectively as a function of reversals of such varying conditions, and means providing a lost motion connection between said elements which connection subject to take up of such lost motion subjects the first mentioned element to positive actuation in reverse directions according to the direction of movement of the second mentioned element, the last mentioned means including means to adjust the range of such lost motion, thereby to provide for adjustment of differential independently of the adjustment of said means responsive to varying conditions.

8. In combination, a snap action device biased to a given position and requiring for operation to another given position application of a force

greater than that required to restrain it against return movement, a cooperating element movable in opposite directions and having means constantly biasing it unidirectionally to subject said device to a non-operating force sufficient to neutralize the bias of said device to restrain said device against return movement, means responsive to varying conditions including an element movable in reverse directions selectively as a function of reversals of such varying conditions, and means providing a lost motion connection between said elements which connection subject to take-up of such lost motion subjects the first mentioned element to positive actuation in reverse directions according to the direction of movement of the second mentioned element, the last mentioned means including means to adjust the range of such lost motion, thereby to provide for adjustment of differential independently of the adjustment of said means responsive to varying conditions.

9. In combination, a snap action device biased to a given position and requiring for operation to another given position application of a force greater than that required to restrain it against return movement, two levers, adjustable biasing means for one of said levers biasing it to subject the device to a non-operating force such as to oppose and neutralize the bias of said device to restrain said device against return movement and means providing a lost motion connection between said levers whereby subject to take up of lost motion said biased lever is subject to positive actuation in reverse directions by the other of said levers according to the direction of movement of the latter, said means including means to adjust the range of lost motion.

10. In combination, a snap action device biased to a given position and requiring for operation to another given position application of a force greater than that required to restrain it against return movement, two levers having a common fixed pivotal axis and being in a coplanar relation, one of said levers being an actuator for the other and said levers having relatively adjustable parts to provide a lost motion connection between said levers adjustable in respect of range of lost motion, condition responsive means to oscillate said actuator lever and adjustable biasing means for said other lever subjecting the same to a bias opposed to the bias of said device and adjustable to be non-preponderating but sufficient to neutralize the bias of the device, thereby to render said biased lever effective to restrain the device during reverse take-up of lost motion between said levers after the device has been moved out of the position to which it is biased, said biased lever having a hooked portion for its pivotal bearing and its said biasing means comprising a leaf spring apertured to be slipped onto said lever for confinement of its extremity behind said hooked portion and for obtaining an opposed bearing against the free extremity of said hooked portion.
